ATTORNEY

UNITED STATES PATENT OFFICE.

CHARLES WHITTINGHAM, OF CLEVELAND, OHIO.

DESIGN FOR A GAS-HEATER.

SPECIFICATION forming part of Design No. 23,531, dated July 31, 1894.

Application filed July 9, 1894. Serial No. 517,012. Term of patent 7 years.

To all whom it may concern:

- Be it known that I, CHARLES WHITTINGHAM, a citizen of the United States, residing at Cleveland, in the county of Cuyahoga and State of Ohio, have invented and produced a new and original Design for Gas-Heaters, of which the following is a specification, reference being had to the accompanying drawing, showing a part thereof.
- 10 The single figure of the drawing illustrates my design which is comprised in the heater as an entirety.
- 15 A is the body of the heater; B the base, and C the top. The body A is cylindrical in general contour from end to end, and has beads —2— at intervals extending horizontally around it, and a belt or belts of openings —3— grouped to form an ornamental circle around the body.
- 20 The base B is circular horizontally, and its top surface inclines at less than forty-five degrees in almost a perfectly straight line from the light ornamental border —6— about the top of the base to the lower and outer edge
- 25 —7— thereof. The legs D are set at a decided inclination to a vertical plane and have flutes —9— longitudinally running into corresponding ornamentations —10— on the base

just above the legs. The surface of the base between the legs and the ornamentations 30 —10— is unfigured.

The top C of the heater has a crown —12— at its center surrounded by a scalloped ring —13— set apart somewhat from its base, and an ornamental nearly flat border —14— extends outwardly from this ring some considerable distance beyond the body A and terminates in a rim —15—. What may be termed substantially leaf shaped projections —16— at infrequent intervals overhang 40 and extend down below the rim —15— and two of these projections show at the sides respectively in a directly front view of the heater. The crown —12— is surmounted by a decorative comb —17—, resting on a short 45 stem and pedestal which give it relief and individuality.

Having thus described my invention, what I claim as new, and desire to secure by Letters Patent, is—

The design for a gas heater substantially as herein shown and described.

CHARLES WHITTINGHAM.
